(57) **CLAIM**

We claim the ornamental design for a dental cleaning appliance, as shown and described.

DESCRIPTION

FIG. 1 is a perspective view of a dental cleaning appliance showing our new design;

FIG. 2 is a front view thereof;

FIG. 3 is a rear view thereof;

FIG. 4 is a side view thereof;

FIG. 5 is a side view of the opposite side of FIG. 4;

FIG. 6 is a top view thereof; and,

FIG. 7 is a bottom view thereof.

Portions of the dental cleaning appliance shown in FIGS. 1–6 are illustrated with gray shading to show color contrast.

The broken lines shown in the drawings illustrate portions of a dental cleaning appliance that form no part of the claimed design.
